UNITED STATES PATENT OFFICE.

WILLIAM H. H. GLOVER, OF SOUTHOLD, NEW YORK.

IMPROVED APPARATUS FOR EXTRACTING OIL FROM FISH.

Specification forming part of Letters Patent No. 96,315, dated November 2, 1869.

Specification of certain Improvements in Presses for Pressing Fish, invented by WILLIAM H. H. GLOVER, of Southold, in the county of Suffolk, and State of New York.

Nature and Objects of the Invention.

My present invention, as its title indicates, has reference to an apparatus for extracting the oil from fish by pressure, and is designed to improve the construction set forth in the Letters Patent of the United States, granted to Israel Peck and myself, dated May 19, 1863.

The principal features of my present invention relate to the combination of the press and of boxes, having open bottoms, and hung in a revolving frame, with a stationary table at the point, at which they are filled, to support the material which is to be compressed; the combination of the press-boxes, having open bottoms, with a bottom where pressure is applied, which is arranged to be moved upward by the power of the press, to give the necessary pressure, while the ascent of the material is resisted by a stationary platen or cover; the combination, with the press-boxes and with the bottom above mentioned, have lugs, or their equivalent, to secure the two together, and support the bottom of the press-box, and prevent its spreading; and the construction of the press-boxes, in the form hereinafter described, by which nearly all the space in the revolving frame is utilized, as hereinafter more fully set forth.

Description of the Accompanying Drawings.

Figure 1 is a side elevation of my improved machine.

Figure 2 is a plan of the same.

Figure 3 is a horizontal section of one of the press-boxes.

Figure 4 is a vertical transverse section of the bottom, on which the press-boxes are supported and elevated when the material is pressed.

A B C D and E E E E are parts of the stationary frame of the machine, A being the part which forms the lower portion of the frame, B being the part which forms the middle portion of the main frame, C being the side portion of the frame, which supports the bed on which the press-boxes are filled, D being the cap, to which the platen of the press is attached, and E E E E being the rods which

secure the previously-described parts of the frame together.

The parts A, B, C, and D may be made of cast-iron, but the rods or standards E should be made of wrought-iron.

The side portion C, of the frame, is supported on the standard E, which is shown at the left hand in figs. 1 and 2, and firmly attached thereto, so as to support the filling-table F, which is firmly attached to it. This filling-table F is made of the proper size and form to form a bottom for one of the press-boxes, and thus preventing the material to be pressed from falling out of the press-box while said box is being filled.

G is the revolving frame, in which the press-boxes are hung upon pins, a, which extend from the revolving frame through the interstices in the sides of the press-boxes, as shown.

H H H are the press-boxes, in which the material to be pressed is placed.

These are made of the form shown in the drawings, so as to occupy all the available space in the frame G, or nearly so. Their sides are made up of a series of slats, like grate-bars, so as to form openings for the oil to escape. The said boxes are open at the bottom, as already mentioned, and as shown in figs. 2 and 3. These press-boxes are three in number, so that while the material in one of them is being pressed, another of the boxes may be filled, and the pressed material discharged from the third.

I is a lever, which is connected to the revolving frame by a ratchet-clutch, to facilitate the turning of said frame, so as to bring the press-boxes into position.

It is well to place a piece of tin, or other sheet-metal, J, between the press-boxes, to prevent oil from spitting in that direction when the material is pressed.

K is the platen of the press, which is firmly attached to the cap D, and is stationary. It is made to fit loosely into the interior of the press-boxes, one of which, when the pressure is applied, is raised up, so as to cause the said platen to enter the box and bear upon the material which is being pressed.

L is the bed, on which the material is pressed. It is made of the same form and size as the bottom of one of the press-boxes, and is firmly attached to the plunger of the hydrostatic press M, though any other suitable means of

applying the pressure may be adopted. The said bed L is slotted like a grate, to allow the oil to escape through its bottom.

It is also provided with lugs, or projections, b b, which, when one of the press-boxes is swung into place, catch over corresponding lugs, c c, formed upon the press-box at the bottom.

It will be well to hang a piece of canvas, or something equivalent, against the outside of the machine, opposite the position of the press-box which may be under the platen, to prevent the oil from spouting around the room.

Operation.

One of the press-boxes, being brought to the proper position for filling over the filling-table, is first filled with the material to be pressed, the revolving frame is then turned against the sun, so as to bring the same press-box under the platen, when pressure being applied, the bed L is raised up, and with it the press-box, so as to press the material between the platen and the bed, and discharge the oil. This having been done, the bed L and the press-box are lowered to the position shown in the drawings, and the next press-box having been filled, it is brought around

to the same position under the platen, and over the bed L, and the material it contained subjected to the same operation, while the material that has been already pressed being removed from over the bed L is discharged, and another box which is over the filling-table may be filled.

Claims.

I claim, as my invention—

1. The combination of the stationary platen K, sliding press-box H, and bed L.
2. The combination of the bed L, press-box H, and lugs b and c.
3. The combination of the revolving frame G, stationary platen K, bed L, and sliding press-box H.
4. The combination of the stationary filling-table F, revolving frame G, sliding press-boxes H, platen K, and elevating-bed L.
5. The combination of the revolving frame G and press-boxes H, the latter being constructed in the form described, so as to utilize the available space of the revolving frame, substantially as hereinbefore set forth.
